CLAIM

The ornamental design for a sports goal target, as shown and described.

DESCRIPTION

FIG. 1 is a front isometric view of my new ornamental design for a sports goal target in accordance with the present disclosure disposed in a lacrosse goal frame including other target goals;

FIG. 2 is a front elevational view thereof; and,

FIG. 3 is a rear elevational view thereof.

The broken lines in the figures depict portions of the sports goal target that form no part of the claimed design.

The top, bottom, left-side, and right-side views of the article are not shown in the drawings or described in the specifications it is understood that the appearance of any part of the article not shown in the drawings or described in the specification forms no part of the claimed design. As such, the determination of patentability is based on the design for the article shown and described.
